UNITED STATES PATENT OFFICE

LOUIS E. GODFRIAUX, OF MADISON, WISCONSIN, ASSIGNOR TO GISHOLT MACHINE COMPANY, OF MADISON, WISCONSIN, A CORPORATION OF WISCONSIN

LATHE

Application filed April 16, 1926. Serial No. 102,577.

This invention relates to lathes, and has reference more particularly to a lathe of the type disclosed in my former Patent No. 1,446,557, dated February 27, 1923, which is characterized by the employment, in combination with the headstock, spindle and chuck, and bed, of a table slidable on the bed toward and from the chuck and having a flat top surface, one or more tool slide bases adapted to be detachably secured on the table at any predetermined point and angle required by the job in hand, tool slides on the bases, slide feed mechanism in the bases, a feed shaft, and driving connections from the latter to the slide feed mechanism continuously in gear with the feed shaft.

My present invention is in the nature of an improvement on the lathe of my former patent aforesaid, and has for its principal objects to provide an improved drive from the feed shaft to the slide feed mechanism, to provide an improved quick return mechanism for the slide, to provide an improved automatic spindle speed control mechanism, and to provide an improved automatic feed direction control mechanism.

Other objects and advantages of the invention will be apparent to persons skilled in the art as the same becomes better understood by reference to the following detail description, taken in connection with the accompanying drawings, wherein I have illustrated a practical working embodiment of the principle of the invention, and in which—

Fig. 1 is a front side elevation, partly in longitudinal section, of the lathe;

Fig. 2 is a vertical longitudinal section;

Fig. 3 is a vertical transverse section through the headstock;

Fig. 4 is a top plan, in horizontal section through the headstock;

Fig. 5 is a rear side elevation of the headstock portion of the lathe;

Fig. 6 is an end elevation of the bed and table, showing the chain and sprocket drive of the slide feeds;

Fig. 7 is an enlarged longitudinal section through the clutches controlling the forward and reverse feeds;

Figs. 8 and 9 are enlarged side elevations

of the clutch shifting lever that controls the forward and reverse slide feeds and the trip-actuated controlling and actuating mechanism therefor, showing different positions of the trip dog relatively to the cam which engages the same;

Figs. 10 and 11 are side and edge elevations of the cam disc showing the oppositely inclined peripheral cam grooves; and

Fig. 12 is an enlarged vertical section through one of the tool slides.

Referring to the drawings, 1 designates as an entirety the head stock frame and housing, at the top of which is journaled the spindle 2 carrying at its forward end the chuck 3; the spindle and chuck being shown as equipped with a compressed air device 4 for operating the chuck jaws. 5 designates as an entirety the bed equipped with suitable ways on which is slidably mounted a table 6 having a broad flat top surface on which may be mounted in any position or positions desired or required by the work one or more tool carriers each comprising a slide base 7 adapted to be detachably fastened to the top of the table 6 as by machine screws 7' passed through holes in side flanges 7" of the base and screwed into tapped holes in the table top (Fig. 2), and a slide proper 8 mounted on the slide base and itself carrying the tool holder 9.

10 designates the power shaft equipped at its outer end with the usual pulley 11 and running at constant speed. Loose on shaft 10 are a pair of clutches 12 and 13 adapted to be clutched to the shaft 10 through the agency of the usual intermediate slider 14. The hubs of clutches 12 and 13 carry small and large diameter driving gears 15 and 16 respectively meshing with large and small diameter driven gears 17 and 18 on intermediate shaft 19, whereby the latter shaft is driven at relatively slow or fast speeds accordingly as the clutch 12 or 13 is engaged. Intermediate shaft 19 drives back gear shaft 20 through change gears 21, 22, and on the forward end of shaft 20 is a pinion 23 meshing with and driving a ring gear 24 on the chuck 3. The parts as thus far described are or may be all as usual in lathes of this general type.

Describing now the feed for the tool slide or slides 8, this is obtained from the spindle 2 through the following mechanism. Fast on the spindle 2 is a spiral gear 25 meshing with and driving a spiral gear 26 fast on an underlying cross-shaft 27. This latter, through change gears 28, 29 and 30 (Fig. 1) drives an underlying transverse shaft 31, fast on which latter is a spiral gear 32 (Fig. 2) engaging and driving a spiral gear 33 on a clutch 34 mounted on a feed shaft 35. On shaft 35 is another clutch 36 through which reverse feed is effected, this clutch carrying a spiral gear 37 driven by a spiral gear 38 of opposite pitch to the spiral gear 32 that is 10 slidable on a transverse shaft 39 disposed parallel with the transverse shaft 31, and driven from the latter through change gears 30, 40 and 41 (Fig. 1). Spiral gear 38 is slidable on shaft 39 in order to enable it to be 15 taken out of mesh with gear 37 when a "quick return" of the tool slide is desired, as hereinafter explained. On shaft 35 between the loose clutch 34 and 36 is a slider 20 42 through the agency of which either clutch is drivingly connected to the shaft. Connected to one end of the shaft 35 by a coupling sleeve 43 is a feed shaft 44 on which is splined a sleeve 45 having a bearing in a bracket 46 attached to the lower side of the 25 forward end of the table 6. Fast on one end of the sleeve 45 is a drive sprocket 47 which, through a chain 48, drives a pair of sprockets 49 and 50 (Fig. 6) each fast on a shaft 51 30 journaled in pillow blocks 52 adjustable along a T slot 53 at the back end of the table 6. Where three slides are used on the table, the drive chain 48 is engaged with an intermediate sprocket 54, the shaft of which is journaled in an intermediate pillow block 55 likewise adjustable in the T slot 53, and carrying idler sprockets 56 and 57 on either 35 side of the driven sprocket 54. Manifestly additional sprockets and pillow blocks can be provided to correspond with the number of tool slides required. Each sprocket shaft 51 is connected, preferably by a universal joint 40 coupling 58, to a shaft 59, which latter is connected by a sleeve coupling 60 to a short shaft 61 (Fig. 12) that is journaled in a swiveled bearing member 62, said bearing member being pivotally mounted on the lower reduced end of a vertical shaft 63 journaled in the slide base 7. Co-operating bevel gears 64 and 65 on the shafts 61 and 63 respectively transmit the drive to the shaft 63, on which latter is a worm 66 driving a worm wheel 67 mounted on a horizontal shaft 68 in the slide base. On shaft 68 is a bevel gear 69 driving a bevel gear 70 fast on a rotary spiral cam 71 suitably journaled in the slide base. In the slide 8 is a stud 72 carrying a roller 73 engaged with the spiral groove of the cam 71 to advance and retract the slide as the cam is rotated. The construction

readily permits the substitution of cams having different pitches to obtain the combination of feeds desired for the tool carried on the slide, and the cam may also be arranged with increasing or decreasing pitch as the cut proceeds and with a straight groove at the end to give a "dwell" or clean-up cut just before the feed is reversed and the tool slide retracted. 70

The slide and feed cam construction herein shown and last above described is substantially identical with that disclosed in my former Patent No. 1,524,860, February 3, 1925, to which reference may be had for a more detailed description. 75

Sprockets 49, 50 and 54 of varying numbers of teeth may be employed to thereby obtain different ratios of feed for and between the slides; and the adjustability of the pillow blocks transversely of the table, 80 the universal joints 58 in the transmission shafts for the slides, and the swiveled connection between the shafts 61 and 63, all contribute to a high degree of flexibility in the set-up, enabling the slides to be positioned 85 parallel with, crosswise of, or at any intermediate angle to the longitudinal median line of the table without the necessity of changing the slide drive. By employing the coupling sleeve 60 to drivingly connect the 90 shafts 59 and 61, it is unnecessary to make the shaft 59 of exact length, and considerable variation in the fore and aft adjustment of the slide is possible. The presence of the universal joint 58 also makes it 95 unnecessary to accurately line up the shafts 51 and 61, as well as enabling the slides to be set at varying angles. The shafts 51, 59 and 61 with their couplings 58 and 60 manifestly constitute a flexible transmission shaft 100 between the slide feed mechanism and an edge 105 of the table.

Where but a single slide is used, the intermediate pillow block and its sprocket may be omitted, and either of the end sprockets 49, 110 50, used as an idler.

As hereinbefore stated, clutch 34 on shaft 35 is employed for forward feed of the slide, and clutch 36, rotating in the opposite direction, is employed for reverse feed of the 115 slide. Loose on shaft 35 is a sprocket hub 74 (Figs. 2 and 7) carrying sprocket wheels 75 and 76. Sprocket wheel 75 is driven at high speed by a chain 77 from a sprocket 78 on the pulley shaft 10 (Fig. 4); and when 120 it is desired to have a "quick return" of the cam slides, instead of reverse feed, the spiral gear 38 is slipped endwise out of mesh with spiral gear 37, and a spring-pressed pin 79 (Fig. 7) mounted in the hub of the clutch 125 36 (and normally locked in retracted position within the hub) is engaged with the rapid traverse sprocket 75, so that when the slider 42 is shifted into engagement with clutch 36, a rapid traverse motion is trans- 130

mitted through the feed shaft and the described transmission to the cams in the tool slides.

Describing next the mechanism for traversing the table 6 back and forth, journaled in and lengthwise of the lower portion of the headstock and bed is a combined trip and table power mover shaft preferably made in two aligned sections 80, 81 (Fig. 2) connected by a coupling 82. This shaft is continuously driven at constant speed from sprocket 76 through a chain 83 and sprocket and safety ratchet 84 to shaft 80. On the opposite end of shaft 81 are secured a sprocket wheel 85 and a spur gear 86, the sprocket wheel 85 through a chain 87 and sprocket wheel 88 drives a clutch 89 loose on a countershaft 90 in one direction, and the spur gear 86 through a spur gear 91 drives a clutch 92 on the countershaft 90 in the reverse direction. Between the clutches 89 and 92 is a slider 93 adapted to drivingly connect either clutch to the shaft 90. Keyed on the shaft 90 is a sprocket wheel 94 that is connected by a sprocket chain to a sprocket 96 (Fig. 1) fast with a safety clutch 97 on a lead screw 98 suitably journaled on the front of the machine. The lead screw 98 is engaged with a stationary nut 99 carried by a bracket 100 that is bolted to the under side of the table 6. Clutch slider 93 is operated from a hand lever 101 (Fig. 1) through a link 102, an arm 103 fast on a transverse shaft 104 journaled in the side of the bed, and a forked clutch shifter arm 105 (Fig. 2) also fast on shaft 104. Manifestly, by swinging the hand lever 101 in either direction from a central or neutral position, rapid traverse movement of the table 6 in the desired direction is effected.

Fast on the trip and table power mover shaft 80 is a continuously rotating disc 106 in which are formed cams through which both the reversing of the slide feed and the changing of the spindle speed are automatically or manually effected. Describing first the mechanism through which the said cam disc effects the automatic reversal of the feed, fast on feed shaft 35 is a spiral gear 107 meshing with and driving a spiral gear 108 fast on an underlying transverse shaft 109 that extends through both side walls of the headstock housing. Referring to Fig. 1, on the end of the shaft 109 which projects through the front wall is an index dial 110 adjustably mounted on the periphery of which are trip dogs 111 and 112, these dogs being offset laterally of the periphery of the dial disc so as to occupy different paths. By setting one of the dogs to the required position on the disc the length of the forward feed of the tool block slides is determined, and by setting the other dog to the required position the length of the reverse feed of the tool block slides is determined. Beneath and

parallel with the dial shaft 109 is a shaft 113 also projecting through the front and rear walls of the headstock housing, and loose on the front projecting end of shaft 113 is a three-arm lever, the two upper arms of which have mounted therein plugs 114 and 115 adapted to be tripped by the dogs 111 and 112 respectively. The depending arm 116 of this lever is connected by a link 117 to an upstanding arm 118 fast on a stub shaft 119 journaled in the lower portion of the front side wall of the housing, as clearly shown in Fig. 1. On the inner end of shaft 119 is a cylinder 120 (Fig. 3) in which is mounted a spring-pressed plunger 121 formed with a V-shaped upper end 122. Journaled in the headstock housing directly above and transverse to the axis of the cam disc 106 is a shaft 123 (Fig. 3), on which is journaled the elongated hub 124 of a clutch shifter arm 125 that straddles and actuates the clutch slider 42 controlling the forward and reverse feed clutches 34 and 36. Journaled on the hub 124 is a lever, the upstanding arm 126 of which is adjustably coupled to the clutch arm 90 125 to actuate the latter. The depending arm 127 of said lever carries on its lower end and projecting from its inner edge a feed trip dog 128 that normally lies opposite one side or the other of the continuously rotating cam disc 106. The periphery of said disc is formed with four slots extending obliquely thereacross (Figs. 10 and 11), two of these slots designated by 129, located one hundred and eighty degrees apart, being inclined in one direction, and the alternating slots designated by 130 being inclined in the reverse direction. When the mechanism is tripped either by one of the dial dogs 111, 112, or by the foot of the operator through a foot pedal 131 fast 100 on the stub shaft 119, the feed trip dog 128 is pressed against the side of the cam disc 106 by the mechanism best shown in Figs. 8 and 9, wherein it will be seen that the outer side of the lever arm 127 carries at its lower end a shoe 132, the lower edge of which is formed with a wide central V notch 133 and on either side thereof with cam inclines 134. The pointed end 122 of the plunger 121 normally lies against one of the cam inclines 134 and holds the feed trip dog 128 from engaging with the constantly rotating cam disc 106 so that it will not enter any of the grooves of the latter. But when, as stated, the mechanism is tripped, the pointed head of the plunger rides into engagement with the adjacent side of the V notch 133, as shown in Fig. 9, thus pressing the feed trip dog 128 against the cam disc, so that when the dog registers with the end of the proper cam groove it drops into the latter, and the rotation of the cam disc swings the lever arm to the opposite side and actuates the clutch slider, reversing the direction of the feed. This action carries the pointed head of the 110 120 125 130 135 140 145 150 155 160 165 170 175 180 185 190 195 200

plunger across and out of the notch 133 and into engagement with the cam surface 134 on the other side of the shoe, so that the feed trip dog is maintained idle until the trip mechanism is actuated in the reverse direction. Should the feed trip dog enter one of the grooves inclined in the wrong direction, it is at once ejected and falls into the next groove by which it is positively carried across to the opposite side.

The automatic spindle speed-changing mechanism is very largely a duplicate of the automatic feed-reversing mechanism last above described. Briefly describing the same, fast on the other end of the shaft 109 which overhangs the rear side of the housing (Fig. 5) is a dial disc 110', adjustable on the periphery of which are laterally offset trip dogs 111', 112', adapted to engage with plugs 113' and 114' mounted in the two upper arms of a three-arm lever fast on the corresponding end of the shaft 113. The depending arm 116' of this lever is connected by a link 117' to an upstanding arm 118' fast on a stub shaft 119' journaled in the rear wall of the housing. On the inner end of shaft 119' is a cylinder 120' carrying a spring-pressed plunger 121' formed with a pointed upper end or head 122'. Said plunger co-operates with a shoe 132, identical with the shoe 132, mounted on the outer edge of the depending arm 127' of a lever journaled on the shaft 123. On the inner edge of lever arm 127' is carried the speed trip dog 128' which functions with the grooves of the cam disc in precisely the same way as the feed trip dog 128 previously described. The upper arm 126' of the lever is adjustably coupled to a lever 125' carrying a fork straddling and actuating the slider 14 that controls the speed-varying clutches 12 and 13. This speed-changing mechanism may also be foot-operated when desired by means of a pedal 135 (Fig. 1) fast on the shaft 113 on the front side of the machine. When the feed reverse or spindle speed is tripped by the foot pedals it is, of course, necessary that the foot pedal be held down until the trip has completed its cycle, in order to insure that the spring-pressed plunger is brought into engagement with the cam surface on the opposite side of the lever arm shoe, thus preventing the trip dog being carried alternately from side to side by the cam disc. During an automatic trip this feature is accomplished by the dial dog holding down its lever until the trip cycle is completed, in which position it remains until the opposite arm of the lever is depressed by the reverse travel of the trip dial and the other dog.

Briefly describing a cycle of operation, and assuming that the table 6 is in its rearmost position, the work is placed in the chuck 3, and the slide bases 7 are secured on the table 6 at the positions and angles required for the job in hand. The feed trip dogs 111 and 112

are set on the index dial 110' at positions which will reverse the forward and backward feeds of the tool slides at the proper times depending on the depth of the cut to be made. Also the spindle speed trip dogs 111' and 112' are set on the index dial 110' at positions which will change the spindle speed between fast and slow at the required times. Through the hand lever 101, the forward rapid traverse of the table is thrown in and maintained until the tool slides have been brought into operate propinquity to the work. The forward feed is then thrown in by one of the trip dogs 111, 112, and continues until the other dog, through the described mechanism, shifts the clutch 42, thus arresting the forward feed and throwing in the reverse feed. When a change of speed is desired, either during a forward or reverse feed, or between said feeds, this is automatically effected by one of the trip dogs 111', and 112' acting through the described mechanism to shift clutch 14, thus arresting the slow speed and throwing in the fast speed, or arresting the fast speed and throwing in the slow speed. If a quick return of the tool slide is required, instead of a reverse feed, this is obtained by slipping the spiral gear 38 out of mesh with spiral gear 37 and, by means of pin 79, locking the hub of clutch 36 to rapid transverse sprocket 75. At the conclusion of the job, rapid backward traverse of the table is effected through proper manipulation of the hand lever 101, a new piece of work is placed in the chuck, the trip dogs are reset if the new work requires different lengths of feed and different spindle speeds, and the described cycle is repeated.

From the foregoing it will be observed that my present machine employs speed-reversing and speed-changing mechanisms both of which are actuated by a single constantly running disc equipped with automatically selective and non-interfering cams for both operations, and both automatic and manual trip mechanisms for said feed-reversing and speed-changing mechanisms; and, furthermore, that the parts of the feed-reversing and speed-changing mechanisms are to a large extent duplicates and hence interchangeable, and the same is true of the respective strip mechanisms for operating them. Manifestly, this represents a considerable economy in the cost and maintenance of the machine and in the ease and facility of renewing worn or broken parts.

While I have herein illustrated and described a practical embodiment of the invention which in practice has been found to satisfactorily effectuate the stated purposes and objects thereof, it is manifest that many of the details of structure and arrangement may be varied and modified without involving any departure from the substance of the invention or sacrificing any of the

advantages and utilities thereof. Hence, I do not limit the invention to the particular embodiment disclosed for purposes of illustration, but reserve all such variations and 5 modifications as fall within the spirit and purview of the appended claims.

I claim—

1. In a lathe, the combination with the 10 spindle, chuck, and bed, of a flat table slideable on the bed toward and from the chuck, a plurality of slide bases and means for fastening the same on said table, tool slides on said bases, independent slide feed mechanisms in said bases, a feed shaft driven from 15 the spindle, flexible transmission shafts drivingly connected at one end to the respective slide feed mechanisms and extending thence over said table to an edge portion of the latter, and complemental transmission gearing continuously in gear with 20 said feed shaft and transmitting movement from the latter to the other ends of said flexible transmission shafts.

2. The combination defined in claim 1, 25 wherein the complemental transmission gearing consists of a driving sprocket wheel splined on said feed shaft, driven sprocket wheels on said flexible transmission shafts, and a single chain trained over said driving 30 and driven sprocket wheels.

3. The combination as per claim 1, wherein the feed shaft extends beneath the table in the direction of movement of the latter, and the flexible transmission shafts carrying 35 the driven sprocket wheels are journaled in pillow blocks mounted on and adjustable crosswise of the table.

4. In a lathe, the combination of a pulley shaft, a spindle and chuck, differential speed 40 power transmissions from said pulley shaft to said spindle and chuck including a pair of clutches respectively controlling said transmissions, a clutch slider controlling both of said clutches, a lever for shifting said clutch slider, a speed trip dog carried by said lever, a continuously rotating disc formed with a cam for actuating said speed trip dog, means normally holding said dog disengaged from said cam, and adjustable 45 trip mechanism for automatically shifting said dog into the path of said cam at any predetermined point in the operation of the lathe.

5. The combination recited in claim 4, 50 wherein the cam is formed as a pair of oppositely inclined oblique grooves across the periphery of the continuously rotating disc, and the speed dog lies opposite one side of the peripheral portion of said disc when one 55 of said clutches is active, and opposite the other side when the other clutch is active.

6. In a lathe, the combination of a spindle, a tool slide, mechanism for actuating said tool slide from said spindle, said mechanism 60 including a pair of oppositely rotating

clutches and a clutch slider controlling the same for transmitting forward and reverse feeds to said tool slide, a lever for shifting said clutch slider, a feed trip dog carried by said lever, a continuously rotating disc formed with a cam for actuating said feed trip dog, means normally holding said dog disengaged from said cam, and adjustable trip mechanism for automatically shifting said dog into the path of said cam to trip out one feed and trip in the other at any predetermined point in the operation of the lathe. 70

7. The combination recited in claim 6, 75 wherein the cam consists of two oppositely inclined oblique grooves formed across the periphery of the disc, and the feed dog lies opposite one side of the peripheral portion of the disc when one of the feed direction controlling clutches is active and opposite the other side when the other feed direction controlling clutch is active. 80

8. In a lathe, the combination of a pulley shaft, a spindle and chuck, differential speed power transmissions from said pulley shaft to said spindle and chuck including a pair of clutches respectively controlling said transmissions, a clutch slider controlling both of said clutches, a lever for shifting said clutch slider, a speed trip dog carried by said lever, a cam for actuating said speed trip dog, means normally holding said dog disengaged from said cam, trip mechanism for automatically shifting said dog into the path of said cam at any predetermined point in the operation of the lathe, a tool slide, mechanism for actuating said tool slide from said spindle, said mechanism including a pair of oppositely rotating clutches and a clutch slider controlling the same for transmitting forward and 90

reverse feeds to said tool slide, a lever for shifting said last-named clutch slider, a feed trip dog carried by said last-named lever, a cam for actuating said last-named feed trip dog, means normally holding said last-named dog disengaged from said last-named cam, and trip mechanism for automatically shifting said last-named dog into the path of said last-named cam to trip out one feed and trip in the other at any predetermined operation of the lathe; both said speed changing and feed reversing cams being formed in the periphery of a single continuously rotating cam disc lying between the levers carrying the speed trip and the feed trip dogs. 100

9. A lathe embodying the combination of claim 4, and wherein the speed trip and feed trip dogs are structurally identical and interchangeable and their respective devices for holding them disengaged from their cams are likewise structurally identical and interchangeable. 110

10. In a lathe embodying the combination of claim 6, and wherein the mechanism for actuating the tool slide from the spindle in- 115

cludes a feed shaft on which the forward and reverse clutches are mounted, and a separable drive gear for the reverse feed clutch, means for effecting rapid rotation of said feed shaft through said reverse feed clutch whereby to effect quick return movements of the tool slide.
